UNITED STATES PATENT OFFICE.

ERNEST R. WOLFE, OF KUSHEQUA, PENNSYLVANIA, ASSIGNOR OF ONE-HALF TO T. E. MOULTON, OF SAME PLACE.

LOCK FOR DOG ATTACHMENTS OF LOGGING-CARS.

SPECIFICATION forming part of Letters Patent No. 601,419, dated March 29, 1898.

Application filed December 29, 1897. Serial No. 664,269. (No model.)

To all whom it may concern:

Be it known that I, ERNEST R. WOLFE, a citizen of the United States, residing at Kush-
equa, in the county of McKean and State of
Pennsylvania, have invented a new and use-
5 ful Lock for Dog Attachments of Logging-
Cars, of which the following is a specification.

The invention relates to improvements in
locks for standards or dog attachments of
10 logging-cars.

The object of the present invention is to
improve the construction of locks for stand-
ards or dog attachments of logging-cars and
to provide a simple, inexpensive, and efficient
15 device capable of locking a pair of dogs or
standards in their engaging position and of
releasing either one without affecting the
other to enable logs to be discharged at either
side.

20 The invention consists in the construction
and novel combination and arrangement of
parts, as hereinafter fully described, illus-
trated in the accompanying drawings, and
pointed out in the claims hereto appended.

25 In the drawings, Figure 1 is a perspective
view of a portion of a car provided with a
locking device constructed in accordance
with this invention, both standards or dogs
being in their engaging position. Fig. 2 is
30 an elevation, one of the dogs being released.

Like numerals of reference designate cor-
responding parts in both figures of the draw-
ings.

35 11 designate a pair of dogs or standards
pivoted between their ends on bolts 2 on the
end of a car 3 at opposite sides thereof and
adapted, as illustrated in the accompanying
drawings, to project above the car and pre-
40 vent logs from rolling off the same. The
dogs are adapted to be mounted on any con-
struction of logging-car and may be used on
a logging-sled; but they are especially adapt-
ed for the car 3, which is provided with rails
45 and adapted to be loaded by steam. The
standards or dogs, which are disposed at a
slight outward inclination, have their upper
ends rounded at the inner edges, and their
lower ends engage fixed stops 4, mounted on
50 the car at the outer edges of the dogs or
standards and limiting the inward swing of
the upper portions of the same. The out-

ward swing of the upper portion of the dogs
or standards is limited by upper fixed stops
5, mounted on the car, at the outer edges of
the said dogs or standards adjacent to the 55
pivots 2.

The dogs or standards are locked in an up-
right or engaging position by a transverse
rock-shaft 6, journaled on the car in suitable
bearings 7 at the lower ends of the said dogs 60
or standards and provided with lugs or shoul-
ders 8, arranged to engage the same and
adapted when the rock-shaft is partially ro-
tated to be carried out of such engagement
to release one of the dogs or standards and 65
permit the same to be depressed, as illus-
trated in Fig. 2 of the accompanying draw-
ings, in order that logs may be discharged
from that side of the car. When the lugs
are in a vertical position, they engage the 70
dogs or standards, and they are retained in
that position by a substantially L-shaped
spring 9, secured at one end to the car and hav-
ing its other arm bearing against one of the
lugs or shoulders. The spring is also adapt- 75
ed to retain the rock-shaft out of engage-
ment, and the said rock-shaft has its ends
bent at an angle to form handles 10, by means
of which it may be readily operated.

In order to retain one of the dogs or stand- 80
ards in its engaging position when the lugs
or shoulders of the rock-shaft are swung
downward, a fastening device 11 is employed
and is adapted to be arranged in either one
of a pair of openings or sockets 12, which are 85
located at the inner edges of the dogs or
standards near the lower ends thereof. This
fastening device may be readily transferred
from one side of the car to the other, so that
either one of the dogs or standards may be 90
released, while the other is retained in its
engaging position.

It will be clear that the invention possesses
the following advantages: The locking mech- 95
anism is simple and comparatively inexpen-
sive in construction, it is positive and reli-
able in its operation, and it may be readily
mounted upon a logging car or sled. It is
adapted to release a dog or standard at one
100 side of the car and retain the one at the op-
posite side in its engaging position, and the
removable fastening device, which is adapted

to be arranged at either side of the car, will enable either one of the dogs or standards to be released.

Changes in the form, proportion, and minor details of construction may be resorted to without departing from the spirit or sacrificing any of the advantages of this invention.

What I claim is—

1. In a device of the class described, the combination with a car, of a pair of pivotally-mounted dogs or standards located at opposite sides of the car and projecting above the same to retain logs thereon, and a rock-shaft journaled on the car in suitable bearings and provided with lugs or shoulders engaging the lower ends of the dogs or standards and locking them in their engaging position, said rock-shaft being adapted to be rotated to carry the lugs or shoulders away from the dogs or standards for releasing the same, substantially as described.

2. In a device of the class described, the combination with a car, of a pair of pivotally-mounted dogs or standards located at opposite sides of the car and projecting above the same to retain logs thereon, a rock-shaft journaled on the car in suitable bearings and provided with lugs or shoulders engaging the lower ends of the dogs or standards and locking them in their engaging position, said rock-shaft being adapted to be rotated to carry the lugs or shoulders away from the dogs or standards for releasing the same, and a removable fastening device mounted on the car and engaging one of the dogs or standards and locking the same when the rock-shaft is swung

downward, said fastening device being adapted to be arranged at either side of the car to lock either of the dogs or standards, substantially as described.

3. In a device of the class described, the combination with a car, of a pair of dogs or standards pivotally mounted thereon at opposite sides thereof, the upper and lower stops arranged at the outer edges of the dogs or standards, a horizontal rock-shaft provided with lugs or shoulders engaging the inner edges of the lower end of the dogs or standards, and a spring mounted on the car and bearing against the rock-shaft, whereby the lugs are retained in engagement with the dogs or standards, substantially as described.

4. In a device of the class described, the combination with a car, of a pair of dogs or standards pivotally mounted thereon at opposite sides thereof, a rock-shaft provided with lugs or shoulders engaging the dogs or standards at the inner edges thereof, the upper and lower stops mounted on the car and located at the outer edges of the dogs or standards, a spring mounted on the car and engaging one of the lugs, and a fastening device for locking one of the dogs or standards against movement when the lugs are carried away from the same, substantially as described.

In testimony that I claim the foregoing as my own I have hereto affixed my signature in the presence of two witnesses.

ERNEST R. WOLFE.
